(57) **CLAIM**

I claim the ornamental design for a golfbag, as shown.

DESCRIPTION

The claimed golfbag is used for storing golf-equipment and can be carried or drawn.

FIG. 1 is a perspective front view of a golfbag showing my new design.

FIG. 2 is a perspective rear view thereof.

FIG. 3 is a front view thereof.

FIG. 4 is a rear view thereof.

FIG. 5 is a front folded view thereof.

FIG. 6 is a rear folded view thereof; and,

FIG. 7 is a close up of the right side thereof.

1 Claim, 7 Drawing Sheets

FIG. 1

FIG. 2

FIG. 3

FIG. 4

FIG. 5

FIG. 6

FIG. 7
